Primary Examiner — Patricia A Palasik(74) *Attorney, Agent, or Firm* — Christopher J. Owens(57) **CLAIM**

The ornamental design for a wear resistant centrifuge tile, as shown and described.

DESCRIPTION

FIG. 1 is a top-front isometric view of a wear resistant centrifuge tile showing the new design;

FIG. 2 is a top-rear isometric view thereof;

FIG. 3 is a bottom-front isometric view thereof;

FIG. 4 is a bottom-rear isometric view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.
